(57) **CLAIM**

The ornamental design for an audio speaker housing, as shown and described.

DESCRIPTION

FIG. 1 is a front isometric view of an audio speaker housing showing my new design;

FIG. 2 is a top plan view thereof;

FIG. 3 is a right side elevational view thereof, the left side being a mirror image;

FIG. 4 is a front elevational view thereof;

FIG. 5 is a rear elevational view thereof;

FIG. 6 is a bottom plan view thereof; and,

FIG. 7 is a front isometric view thereof; The broken line showing of the other speakers is for illustrative purposes only and forms no part of the claimed design.
